UNITED STATES PATENT OFFICE

GEORGE WATSON WILDER, OF DETROIT, MICHIGAN, ASSIGNOR TO THE YALE & TOWNE MANUFACTURING COMPANY, OF STAMFORD, CONNECTICUT

LOCK

Application filed February 23, 1929. Serial No. 341,931.

This invention relates to locks of the type employing a cylinder plug and sliding tumblers. It is desirable to assemble the plugs and tumblers as a unit to be shipped to the user who merely inserts a key into the plug and then inserts the plug into the locking unit. My invention relates more particularly to means for maintaining the sliding tumblers within the plug while the plug is being shipped and handled prior to its insertion into the lock unit.

Fig. 1 illustrates a front, elevation, and sectional view of a preferred form of my invention. Figures 2 and 3 illustrate modifications of my invention.

Referring more particularly to the drawings, Fig. 1 illustrates a usual type of die cast plug 10 having a keyway 11 and a series of tumbler chambers 12 containing the various sliding tumblers 13. Each of these tumblers is equipped with a shoulder 14, on the underside of which the spring 15 is adapted to press to urge the tumbler in an outward direction. A portion 16 of the edge of each tumbler chamber is staked over the upper surface of each tumbler shoulder 14 to limit the outward movement of the same. This operation is performed after the insertion of the tumblers against the pressure of the springs 15, and acts to maintain the tumblers in the chambers by constricting the size of the openings of the chambers above the shoulders of the tumblers.

Fig. 2 illustrates a sleeve adapted to accomplish a similar result while Fig. 3 shows a wire adapted to be inserted through the keyways of the tumblers to maintain the same in assembled position.

It is obvious that modifications of my invention may be devised by a person skilled in the art without departing from the spirit and scope of the appended claims.

I claim:

1. In a lock, a key plug having a tumbler chamber and a tumbler adapted to reciprocate therein, an edge of said chamber being staked over to limit the outward projection of said tumbler.

2. In a tumbler plug, a tumbler chamber and a tumbler adapted to reciprocate there-

in, an edge of said chamber being staked over after the insertion of the tumbler into the chamber, said staked portion being adapted to limit the outward projection of said tumbler.

3. In a tumbler plug, a tumbler chamber and a tumbler adapted to reciprocate therein, an edge of said chamber being staked over after the insertion of the tumbler into the chamber, said staked portion being cooperable with a part of said tumbler to limit the outward projection of the tumbler.

4. In a tumbler plug, a tumbler chamber, spring means carried by said plug, a tumbler inserted into said chamber against the pressure of said spring means, and a portion of said chamber staked over after the insertion of said tumbler, said staked portion being cooperable with a part of said tumbler to prevent expulsion of the same by said spring means.

5. In a tumbler plug, a tumbler chamber, a tumbler insertible into said chamber, spring means carried by said plug and adapted to press said tumbler outwardly, a portion constituting said plug being adjustable after the insertion of the tumbler, said adjustable portion being cooperable with a part of the tumbler to prevent expulsion of the same from said chamber by said spring.

6. In a tumbler plug, a tumbler chamber having one opening of constricted size and an opening of larger size, a tumbler adapted to enter said chamber only through said larger opening, a portion of said opening being adjustable after insertion of said tumbler to prevent its removal.

7. In a lock, a key plug having a tumbler chamber and a tumbler adapted to reciprocate therein, a shoulder on said tumbler, a spring in said plug adapted to act on the underside of said shoulder so as to project the tumbler from the tumbler chamber, and a portion of said chamber adapted to be staked over to cooperate with the upper side of the shoulder to limit the outward projection of the tumbler.

Signed at Detroit, in the county of Wayne and State of Michigan, this 18th day of February, A. D. 1929.

GEORGE WATSON WILDER. 100
